UNITED STATES PATENT OFFICE.

SOLOMON WISE, OF CINCINNATI, OHIO.

DESIGN FOR A DISPLAY STAND.

Application filed January 4, 1927. Serial No. 20,270. Term of patent 3½ years.

To all whom it may concern:

Be it known that I, SOLOMON WISE, a citizen of the United States, residing at Cincinnati, in the county of Hamilton and State of Ohio, have invented a new, original, and ornamental Design for Display Stands, of which the following is a specification, reference being had to the accompanying drawing, forming part thereof.

In the drawing:—

I claim:—

The ornamental design for a display stand substantially as shown.

SOLOMON WISE.
